ANDREW J. SANFORD, OF NEWARK, OHIO, ASSIGNOR TO A. H. HEISEY & CO., OF NEWARK, OHIO.

DESIGN FOR A BOTTLE.

Application filed August 3, 1920. Serial No. 401,061. Term of patent 3½ years.

To all whom it may concern:

Be it known that I, ANDREW J. SANFORD, a citizen of the United States, residing at Newark, in the county of Licking and State of Ohio, have invented a new, original, and ornamental Design for a Bottle, of which the following is a specification.

The drawing is a side elevation of a bottle embodying the invention. The transparency of the article can not be well delineated by

black and white line drawing, nor can the hollow interior thereof be well illustrated for the same reason. The ornamentation involved in the design resides in the outline or contour, and appearance of the article.

I claim—

The ornamental design for a bottle, as shown.

ANDREW J. SANFORD.
